UNITED STATES PATENT OFFICE.

MARTIN J. LIDE, OF BIRMINGHAM, ALABAMA.

CONCENTRATING TABLE.

Application filed January 26, 1925. Serial No. 4,643.

My invention relates to a concentrating table whereon the material to be treated is received on an inclined riffled table to which are imparted three motions, namely, one vertical and two in different horizontal directions, such motions acting to effect a quick stratification of the material on, and a rapid feed of the material over, the table, thereby increasing its capacity as well as its efficiency. Such a table, broadly speaking, forms the subject matter of my pending application Serial No. 712,589 filed May 12, 1924.

One object of my present invention is to mount the table on yieldable rocker supports and to rigidly connect to the table the mechanism for imparting vertical reciprocation thereto. My object in having this part of the operating mechanism movable with the table is to simplify the construction, reduce the cost, and increase the durability of the machine.

My present invention also contemplates disposing the rocking table supports and all driving mechanism below the table, thereby producing a compact self contained unit and leaving the table clear overhead, which is desirable for many operating reasons.

My present invention further contemplates the novel construction of the rocking stanchions upon which the table is mounted, these comprising flexible or spring portions which leave the table free to follow the various direct and compound motions which are imparted to it by the opposing horizontal drives and the vertical drive.

My invention further contemplates designing these stanchions for simple adjustment as to length, thereby to control the tilting of the table and to regulate its functions according to the material to be worked and the rate of output.

My invention also contemplates an improved design of the table proper having its end discharge in line with the riffles upwardly inclined so as to retard the off-fall of the material at the end of its movement between riffles.

A further feature of my invention relates to the provision of means for adjusting the length of the stroke of the mechanism for imparting horizontal vibrations to the table, such means contemplating the simultaneous adjustment of all mechanism for imparting motion in any given direction and for independent adjustment of the mechanisms for

imparting reciprocations in different directions and for the effecting of such adjustment without interrupting the operation of the table.

My present table is designed as a wet concentrating table so that the particles when catapulted from the table by the vertical reciprocation thereof must fall through a resistant medium which will give a very effective separation, but its various novel features are adaptable for use in other types of concentrating tables.

My invention further comprises the novel details of construction and arrangements of parts, which in their preferred embodiment only are illustrated in the accompanying drawings which form a part of this specification, and in which:

Fig. 1 shows in plan view my improved concentrating table with riffles, feed chute and water box omitted for the sake of clearness.

Fig. 2 is a side elevation; and

Fig. 3 an end elevation of the concentrating mechanism.

Fig. 4 is a detail plan view of the concentrating table proper.

Fig. 5 is a detail view of one of the stanchions.

Fig. 6 is a detail view of the cam and one of the longitudinal rocker drives for the table.

Fig. 7 is a detail view of the upper end of a modified type of stanchion.

Fig. 8 is a detail view of the adjustable eccentric rotating weight for vertically oscillating the table.

Figs. 9, 10 and 11 are cross-sectional views of the table taken respectively on the lines 9—9, 10—10 and 11—11 of Fig. 4, Figs. 9 and 11 being enlarged.

Similar reference numerals refer to similar parts throughout the drawings.

In the embodiment of my invention illustrated, I show a supporting structure comprising four corner uprights 1, 2, 3 and 4, preferably formed by angles which are cross braced by lower horizontal side angle members 5 and end members 6. I mount near each end of the frame on the members 5 a channel 7 and near the ends of these channels, i. e., near the four corners of the frame, I mount the base members 8 of ball bearings whose upper or cap members 9 are slotted for the passage, free for angular play therethrough, of the threaded shanks 10 of the

four stanchions 12, each shank carrying on its lower end a ball 11 which is free to rock in its respective bearing. Each of the stanchions 12, which are alike, has at its lower end a threaded member 13 which, by engagement with the threaded shank 10, permits the adjustment as to length of the stanchion. I provide a square recess 11^a in the under surface of the ball 11, which receives a square projection 8^a in the socket 8. These parts 11^a and 8^a co-act to permit the ball rotating about the vertical axis of the stanchion. At its upper end each stanchion carries a centering pin 14 which is received in the lower end of a coil spring 15, the upper end of which receives a centering pin 16 forming part of the shank for an upper ball 17 which works in a ball bearing generally designated by the numeral 18. These ball bearings 18 are secured to the under-surface of the concentrating table 19 and support it free to rock on the four stanchions.

Along the longitudinal center line of the table, and depending from its under-surface, are aligning bearings 20 which receive a shaft 21 having universal joints 22 on each side of a driving motor 23 for the shaft, said motor being rigidly connected to the under side of the table near its center. Near each end of this shaft 21 I mount an eccentric weight 24, which is shown in detail in Fig. 8 and which is preferably in the form of a double eccentric, the inner member 25 having an opening 26 for the shaft 21 and the key to secure it fast thereon. A set screw 27 holds the two concentrics in the desired adjusted relationship. The action of the fast spinning eccentric weights is to impart rigid vertical oscillations to the whole table, this being permitted, so far as the stanchion supports are concerned, by reason of the springs 15 therein.

As herein shown, the mechanism for imparting two direction horizontal reciprocations to the table consists in a drive by means of a sprocket chain 28 to a sprocket wheel 29 fast on a shaft 30 which is journaled in brackets 31 made fast in any suitable manner to the corner posts 3 and 4 of the frame. The shaft 30 at one end has fast thereon a bevelled pinion 32 which meshes with a similar pinion 33 fast on a shaft 34 journaled, at right angles to shaft 30, in brackets 35 overhung on the side of the frame and rigidly connected to the corner posts 1 and 4 of the frame work. The shaft 30 near each end carries fast thereon an actuating cam 36 which is shown in detail in Fig. 6 in its preferred form. Cams 36 of a similar character are mounted near each end of the shaft 34. As each cam 36 on shaft 30 controls a similar rocker means only one of such rocker means need be described. This rocker element as seen in Fig. 6 comprises a rocker arm 37 carrying

at its lower bifurcated end a journaled roller 38 adapted to engage its respective cam 36. The arm 37 is mounted to rock about an intermediate axis which in the case of the cams on the shaft 30 is formed by a shaft 39 journaled in the upper portion of the brackets 31, and in the case of the cams on the shaft 34, each axis is formed by a shaft 40 journaled in the upper part of the brackets 35. The rocker extends above its axis to form an arm 41 about which a yoke 42 is passed free for vertical adjustment, the yoke at its end away from the machine being threaded to receive a threaded vertical shaft 43 that is used to adjust the position of the yoke relative to the axis of the rocker arm to vary the radius of its angular play. The shaft 43 at its lower end is journaled in a bearing 44 on the arm 41 and carries a bevelled gear 45 which meshes a bevelled gear 46 on a shaft 47 also journaled in the two rockers at the end or at the side of the machine. By turning this shaft 47 by a hand wheel 47^a both yokes 42 can be equally and simultaneously adjusted for the rockers controlled by the shaft 30 or the shaft 34 if desired and such can be made without stopping the machine.

In Fig. 3 I show a simpler form of rocker arm actuated by the cam 36 on the shaft 34. Here the arm 48 extending above the axis of the rocker is provided with a series of openings 49 to receive a bolt which connects a simple clevis or yoke 50 thereto.

The yokes 42 operated by the end rocker arms 41 serve to impart endwise motion to the table by the following means. Each yoke is connected by any flexible connection such as a pivot, see Fig. 2, or by an universal joint 52, see Fig. 6, to its respective operating rod 51, and this in turn is connected by an universal joint 53 to a depending bracket 54. One of these brackets 54 is mounted fast on each side of the table and depends thereunder with a series of attachment holes provided on each side of the bracket. These brackets are equi-distant from the shaft 30 and each has attached thereto a spring 55 interposed between an universal coupling 56 and a rod 57 that in turn is bolted to a rigid support 58 on the under frame. Thus, when the rockers 41 pull the frame endwise to the left, Fig. 2, the springs 55 will act to return it to the right. In like manner, the yokes 50, operated by the side rocker arms 48, act through rods 59, springs 60 and universal couplings 61 to engage end brackets 62 and pull the table sidewise against the action of springs 63 interposed between universal joints 64 connected to the brackets 62, and rods 65 connected to rigid supports 66 on the frame. In each rod of the operating connections described I interpose a turn buckle 67 for the purpose of permitting adjustment of its length and hence control of

the table's position. The brackets 62 make provision for change in the point of attachment of the operating connections to the table. The universal joints permit compound motions being imparted simultaneously to the table, as follows:

By the end rockers 41, lengthwise oscillations.

By the side rockers 48, transverse oscillations, and

By the eccentrics 24, vertical oscillations, and the stanchions rock and yield at the spring connections 15 to allow all such table movements.

If it be desired to avoid any rise and fall of the table as it rocks on its stanchions, this may be accomplished by the arrangement shown in Fig. 7, where bearings 68 are substituted for the ball joints and each has its surface 69 struck on a curve having a radius the length of the stanchion. In the center of the surface 69 is a socket 70 which loosely receives a screw pin 71. This is mounted in the table or base support and is screwed through a flat bearing plate 72 which serves as a washer and contacts with the adjacent surface 69. The pin is loose enough in the socket to permit the limited horizontal motions imparted to the table, and the latter will thus swing laterally in the same plane except as it may be moved from such plane by the vertical oscillations imparted thereto by the weights 24.

The table has the shape of a parallelogram with the acute angles at its highest left corner (see Fig. 4) and lower right corner. At the upper left corner I provide a feed chute 73 and extending along above its higher side edge is a water trough 74 with a perforated bottom to deliver water along the higher side edge of the table. Parallel with its sides I provide longitudinal riffles 75 separated into groups or zones by the spaced higher riffles 76. The riffles are formed of any suitable material and attached in any practical way to the table, which as shown in Fig. 11, has a waterproof covering 77 through which angle iron riffles are bolted to the table which in turn is bolted to a channel iron frame 78. The right hand or discharge end edge of the table is sloped up, as seen in Fig. 9, and the riffles extending thereon are cut away underneath to fit to said incline.

In operation, the material to be treated is delivered to the table by the feed chute and the three table drives are started up, giving to the table high frequency short vertical oscillations and low frequency relatively long horizontal oscillations both lengthwise and transversely. The water and material are thus forced both by the table motions and by its inclination to flow across and lengthwise thereof across the riffles. The vertical oscillations produce a rapid stratification of

the material contemporaneously with its forced movement both lengthwise of and across the riffles by the cam drives. It results that the less dense matter will travel diagonally across the riffles while the denser matter follows the riffles and rides up the incline 79 and falls off the end of the table. The less dense matter falls off the lower side edge of the table.

Many adjustments are possible to accommodate the table to any particular duty. The speed of the motor 23 may be raised and with it the frequency of the vertical oscillations. The eccentrics 25, 24 may be relatively adjusted to vary the length of the vertical vibrations. The speed of drive to the cam shafts 30, 34 may be changed to vary the frequency of the horizontal reciprocations.

The horizontal reciprocations may be varied together or relatively by change in the conformation of the cams 36, or of the position of the yokes 42 or 50 to the rocker axis. The motion of the table can be varied by connecting the horizontal oscillating drives closer thereto or farther therefrom, using the different attachment points on the brackets 54 and 62. The inclination of the table can be varied at will by adjustment of the length of its supporting stanchions.

All of these adjustments provide the widest range of control for the table permitting the compound motions thereof to be so governed and modified as to produce the maximum efficiency of separation as well as capacity for the table. All of the operations described will take place whether or not the material is treated dry on the table or is subjected to some other medium as water or air currents, to modify the separating effect of the table's compound movements. The rising surface 79 at the end of the riffles restores the off-fall of the denser matter which travels parallel with and between the riffles.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. The combination with a concentrating table having means to reciprocate it horizontally and means to vibrate it vertically and a base support, of sectional rocking table supports having universal joint connections to the base support and to the table to permit the table to reciprocate, means to adjust the length of a plurality of said supports, and a spring interposed between the sections of each support to permit free axial

vibratory motion between the end bearings responsive to vertical vibrations.

2. The combination with a concentrating table and a supporting base of a plurality of 5 rocking supports for the table, each support comprising an intermediate sleeve member, a universal bearing element adjustably connected to one end of the sleeve member, a universal bearing element spring mounted 10 for free axial play on the other end of the sleeve member, and bearing elements for the supporting base and table adapted to co-act with said universal bearing elements.

3. The combination with a concentrating 15 table and a supporting base of a plurality of supports, each having universal bearings at each end, a spring supporting one of the universal bearings of each support free to permit vertical vibrations of the table, 20 means to adjust the length of a plurality of said supports, and bearing elements on the base and table which co-act with said universal bearings on the supports.

4. A rocking support for a concentrating

table, comprising a bottom ball joint comprising means to prevent relative rotation of the joint members about the axis of the support, an intermediate supporting section adjustably connected to one of said ball bearing elements, and a universal joint having 25 a spring connecting it to the said intermediate portion and adapted to support the table free for vertical vibrations.

5. A rocking support for concentrating 30 tables and the like, comprising a base socket, a ball bearing adapted to rock in said socket, a support mounted on said ball bearing, means to prevent the ball turning in its socket about the long axis of the support, screw means to adjustably connect the support to the ball, a spring mounted on the support, an upper universal joint member 40 mounted on the spring free for vertical vibrations, and means to connect said upper joint member to a table.

In testimony whereof I affix my signature.

MARTIN J. LIDE.
